UNITED STATES PATENT OFFICE.

FRED A. PUTNAM, OF KEENE, NEW HAMPSHIRE, ASSIGNOR TO MARKEM MACHINE COMPANY, OF BOSTON, MASSACHUSETTS, A CORPORATION OF MASSACHUSETTS.

MARKING MACHINE.

Application filed May 22, 1926. Serial No. 111,068.

This invention relates to improvements in marking machines and the principal object thereof is to provide a machine adapted to mark successively a series of superimposed articles beginning at the lowermost.

A further object of the invention is to provide a machine of the character above described with means for clamping the superimposed articles upon the work support with means for permitting the successively marked articles to be moved from the work support or platen upon which the articles are marked.

A further object of the invention is to provide a novel clamping mechanism which will clamp any desired number of articles upon the work support.

A further object of the invention is to provide a novel mechanism for supporting the printing head which will permit the printing head to be moved from inking position to printing position while maintaining the plane of the printing face in substantial parallelism with the plane of the work support.

A further object of the invention is to provide means for normally supporting the printing head in an elevated position intermediate of the inking mechanism and printing position.

A further object of the invention is to provide a novel mechanism for locking the type in the printing head in such a manner that the individual type can be removed without the necessity of removing the type holder from the printing head.

Other objects and features of the invention will more fully appear from the following description of the accompanying drawing and will be particularly pointed out in the claims.

A preferred embodiment of the invention is illustrated in the accompanying drawings in which Fig. 1 is a side elevation of a machine particularly designed for marking gloves or other flexible articles;

Fig. 2 is an end elevation of the machine viewed from the right toward the left;

Fig. 3 is a detail plan view of the work support illustrating particularly the aperture through which the articles are successively depressed as they are marked;

Fig. 4 is a sectional diagrammatic view illustrating the number of superimposed ar-

ticles carried by the work support and the manner in which the articles are successively depressed through the aperture in the work support as they are printed, and

Fig. 5 is a vertical central sectional view through the printing head on the line 5—5, Fig. 2.

The machine illustrated in the accompanying drawing comprises a base 1 upon one end of which a work support 2 is mounted or formed integral therewith. The work support 2 extends beyond the end of the base 1 to provide a space to permit the marked articles to be depressed beneath it. The portion of the work support which extends over or upon the base desirably is provided with a printing platen 3 of relatively soft material which will not injure the type. The work support is provided with an aperture 4 of sufficient area to permit the portions of flexible articles which have been printed upon the platen to be depressed therethrough and is provided with a sufficiently large surface 5 beyond the aperture to enable a series of superimposed flexible articles 6, such as gloves, shoe uppers and the like, to be clamped thereupon.

Suitable means are provided for clamping the superimposed articles upon the work support. The preferred means illustrated herein comprises a flat plate 7 having at its ends upturned ears 8 which are pivotally mounted upon a rod 9, the ends of which are secured to like parallel links 10 which are pivotally mounted at their lower ends upon bosses 11 extending upwardly from the end portions of the work support.

Suitable means are provided for locking the clamping plate 7 in clamping engagement with the articles 6. In the construction illustrated herein a pair of pawls 12 are pivotally mounted upon the rod 9 and are provided with upwardly extending arms 13 which desirably are connected by a handle member in the form of a rod 14 so that both pawls may be actuated simultaneously. The pawls 12 engage the teeth of like arcuate ratchets 15 which are mounted upon the work support and as shown herein are pivotally supported upon suitable lugs extending upwardly therefrom. Arms 16 extending from the ratchets engage posts 17 projecting upwardly from the work support and serve to hold the ratchets in proper position.

- Springs 18 connected at their upper ends to the arms 13 of the dogs and at their lower ends to the parallel links 10 hold the pawls normally in engagement with the ratchets.
- 5 By reason of this construction the clamping plate 7 can be readily raised to permit the insertion of articles to be marked by grasping the handle member 4 and swinging the same to the left to disengage the pawls from 10 the ratchets, then raising the pawls to the upper portion of the ratchet to provide a space between the clamping member and the work support, the articles having been inserted beneath the clamping plate, are advanced until their ends rest upon the platen 3. The clamping plate will then be forced downward into clamping engagement with the articles and will be locked in clamping position by the engagement of the pawls 12 with the teeth of the ratchets 15. All of 20 the flexible articles to be marked will then be bent upwardly except the lowermost article which is permitted to rest upon a platen.
- 25 Any suitable means for printing the proper mark upon the article may be used, after which the marked article is depressed through the aperture 4 and the next lowermost article from the bottom of the superimposed series dropped upon the platen in marking position. This procedure may be continued until the entire pile of superimposed articles is marked, after which the clamping plate may be removed by disengaging the pawls in the manner aforesaid and raising the clamping plate from engagement with the pile. In thus marking the articles any suitable printing mechanism may be employed. Preferably, however, a 40 printing device is provided which is movably secured to the frame in such manner that it can be swung into co-operative printing relation with the platen and removed from such relation to permit the application 45 of ink to the type.
- In the preferred construction illustrated in the accompanying drawing the printing mechanism comprises a printing head which is so mounted that it may be swung to and 50 from printing position and in its swinging movement maintained with its printing face in substantial parallelism with the plane of the work support. The preferred form of printing head shown in the accompanying 55 drawing comprises a U-shaped body 19 having downwardly extending parallel arms 20 at their lower ends which carry a suitable type-holding member. The printing head 19 is pivotally connected to a pair of 60 parallel links 21, 22 which are pivotally connected at their opposite ends to the ends of parallel rock shafts 23, 24 respectively, which are journaled in bosses 25, 26 extending from a suitable standard 27 mounted upon the base 1. In order to ensure

accuracy of movement of the head the rock shafts 23, 24 have rigidly secured to them other parallel links 28, 29 which are connected together by a link 30.

The base 1 is provided, at the end opposite the work support, with an extension 31 and a disk 32 having an inking pad or pads 33 is rotatably mounted upon the stud 34 upon an extension. The inking pad is, of course, so positioned as to be beneath the type face 75 of the printing head when the latter is swung to one side of the standard, as illustrated in Fig. 1.

The printing head is provided with a handle 35. Desirable means are provided 80 normally to support the printing head in an intermediate position out of engagement with the platen and the inking pad. This preferably is accomplished by supporting the printing head upon a spring 36 which 85 is connected at its lower end to a link 21 and at its upper end to the lateral extension 37 of a rod or post 38 which is detachably seated in the bosses which extend from the standard 27 and support the rock shafts 23 and 24. 90

In the operation of the machine the articles to be marked are placed upon the work support and clamped in the manner above described and all the articles are turned backwardly except the lowermost in 95 such a manner as to leave the lowermost article lying upon the platen 3. The printing head is then passed into engagement with the inking pad, then raised and carried by the links over the vertical plane of the rock 100 shafts and then depressed into printing engagement with the article upon the platen. The printed article is then depressed through the aperture 4 and the next article of the superimposed series permitted to drop upon the platen and the printing head pressed thereupon to mark it. This procedure is continued until all the articles of the pile have 105 been marked. When it is found necessary to replenish the ink upon the type during this marking operation the head is swung again over the plane of the centers of the rock shafts and the printing face brought into engagement with the pad in the manner aforesaid. When the printing is not being done the head is retained in an intermediate elevated position by the lifting spring 36 110 aforesaid.

Another feature of the invention consists 115 in providing novel means for securing the type in the type head in such a manner that the individual type may be inserted therein or removed therefrom from the side opposite that which faces the work support, while the printing head is supported in its normal intermediate position. In the preferred construction illustrated the type-holding means comprises a plate 39 having a bevelled side 40 which engages a complementary undercut bevelled face of an extension 120 125 130

41 of the lower end of the printing head. The opposite side 42 of the plate is similarly bevelled and is engaged by a complementary bevelled end of a dog 43 which is pivotally mounted upon the stud 44 extending from a lateral position 45 on the printing head. The stud 44 is provided with a handle 46 by means of which it may be pivotally moved and the handle is pressed outwardly by a spring 47 so that the bevelled end normally engages the bevelled face of the type-holding member. The type-holding member is provided with a slot or a plurality of slots to receive the type.

15 The type are made of a width to fit within the slots and are provided with shouldered heads to rest upon the upper surface of the type-holding plate 39. The locking member, preferably in the form of a plate 48, engages the upper ends of the type and holds them firmly in printing position and also acts as a backing member to receive the pressure which is imposed upon the type. The backing or locking plate 48 is pivotally mounted 20 on a shaft 49 which is mounted in the arms 20 of the printing head and a suitable stop 50 extending from one of the arms 20 serves to limit the swinging movement of the plate 48 when it is in position to engage the type heads. A helical spring 51, which is secured at its lower end to the swinging locking plate 48 and at its upper end to an eye 52 upon the yoke of the head, serves to retain the locking plate 48 in engagement with the stop 50. The width of the locking member 48 desirably is sufficient to enable its lower edge to swing into substantial tangential relation to the upper ends of the type heads.

40 Desirably an arm 53 extends laterally from the locking plate 48 and provides a convenient handle by which the locking plate 48 may be swung out of locking position against the action of the spring 51.

45 In order to introduce or to replace the type it is merely necessary to press downwardly upon the arm 53 thereby swinging the locking plate 48 out of locking position. The type can then be inserted into the slots in the type-holding member or if type are carried in the type-holding member they may be removed by merely raising them up and new type substituted. Thus a great saving in time which is required for changing the type is saved.

50 If it is desired to remove the type holder and type it is merely necessary to press upon the arm 46 of the dog 43 sufficient to relieve the lower end thereof from engagement with the type-holding plate whereupon the latter will drop out of the lower end of the head and can be readily replaced.

55 The arms 20 of the printing head may, if desired, be also provided with aligned apertured bosses 54 to receive the journals of a

suitable type wheel which may carry several series of different insignia which are to be stamped upon different articles.

The present invention in so far as it relates to the mechanism for locking the type and type holder is a specific embodiment of the broader invention disclosed in my prior application Serial No. 723,974, filed July 3, 1924.

By reason of the present invention a simple and relatively inexpensive machine is provided for marking articles in which a pile of superimposed articles of like size can be readily marked and in which the type required for marking different articles can be rapidly assembled and replaced. As the printing head is normally supported out of engagement with the platen or with the inking device the type extending downwardly is not likely to collect dust, and will not accumulate an excessive amount of ink, as would be the case if the type normally rested upon the inking pad. The machine as a whole comprises a convenient mechanism which is adapted to save considerable time and to ensure accurate and uniform printing of the articles to be marked.

It will be understood that the invention disclosed herein is of an illustrative character and various changes in form, construction and arrangement of parts can be made within the spirit and scope of the following claims.

Having thus described the invention, what is claimed as new and desired to be secured by Letters Patent, is:

1. A marking machine comprising a platen and a work support providing an aperture in proximity to said platen in sufficient area to permit the portion of a flexible article which has been printed upon said platen to be depressed therethrough, whereby a series of superimposed flexible articles may be successively printed from the lowermost upwardly.

2. A marking machine comprising a platen and a work support providing an aperture in proximity to said platen in sufficient area to permit the portion of a flexible article which has been printed upon said platen to be depressed therethrough, whereby a series of superimposed flexible articles may be successively printed from the lowermost upwardly, and means for clamping the series of superimposed articles upon said work support.

3. A marking machine comprising a platen and a work support providing an aperture in proximity to said platen in sufficient area to permit the portion of a flexible article which has been printed upon said platen to be depressed therethrough, whereby a series of superimposed flexible articles may be successively printed from the lowermost upwardly, and a clamp comprising

ing pawl and ratchet mechanism co-operating with said work support to hold said articles firmly in superimposed relation.

4. A marking machine comprising a platen and a work support providing an aperture in proximity to said platen to permit the portion of a flexible article which has been printed upon such platen to be depressed therethrough, a clamping member pivotally mounted upon parallel links co-operating with said work support to clamp a series of superimposed flexible articles therebetween, and means for locking said work-clamping member in work-clamping position.

5. A marking machine comprising a platen and a work support providing an aperture in proximity to said platen to permit the portion of a flexible article which has been printed upon such platen to be depressed therethrough, a clamping member pivotally mounted upon parallel links co-operating with said work support to clamp a series of superimposed flexible articles therebetween, and pawl and ratchet mechanisms located at opposite ends of said clamping member operable to lock said clamping member in different clamping positions.

6. A marking machine comprising a platen and a work support providing an aperture in proximity to said platen to permit the portion of a flexible article which has been printed upon such platen to be depressed therethrough, a pair of links pivotally mounted at the ends of said work supports, a rod connecting said links, a clamping member pivotally mounted on said rod, pawls pivotally mounted on said rod, and arcuate ratchets mounted upon the work support co-operating with respective pawls to lock the clamping member in adjusted positions.

7. A marking machine comprising a platen and a work support providing an aperture in proximity to said platen to permit the portion of a flexible article which has been printed upon such platen to be depressed therethrough, a pair of links pivotally mounted at the ends of said work support, a rod connecting said links, a clamping member pivotally mounted on said rod, spring-actuated pawls pivotally mounted on said rod, a handle member connecting said pawls to operate them simultaneously, and an arcuate ratchet mounted on said base co-operating with the respective pawls.

8. A marking machine comprising a platen and a work support providing an aperture in proximity to said platen in sufficient area to permit the portion of the flexible article which has been printed to be depressed therethrough, a standard mounted upon said work support, a printing head, and means for supporting said head to per-

mit the same to be swung into and out of co-operating relation to said platen.

9. A marking machine comprising a platen and a work support providing an aperture in proximity to said platen in sufficient area to permit the portion of the flexible article which has been printed to be depressed therethrough, a standard mounted on said work support, parallel rock shafts mounted in said standard having parallel arms connecting said shafts to said printing head to permit said head to swing to opposite sides of said standards, and means for applying ink to the type carried by the printing head.

10. A marking machine comprising a platen and a work support providing an aperture in proximity to said platen in sufficient area to permit the portion of the flexible article which has been printed to be depressed therethrough, a standard mounted on said work support, an inking pad located at the other side of said standard from said platen, parallel rock shafts mounted in said standard having parallel arms pivotally connected to said printing head operable to permit the printing head to be swung selectively into co-operative relation to said platen and said inking pad.

11. A marking machine comprising a platen and a work support providing an aperture in proximity to said platen in sufficient area to permit the portion of the flexible article which has been printed to be depressed therethrough, a standard mounted on said work support, an inking pad located at the other side of said standard from said platen, parallel rock shafts mounted in said standard having parallel arms pivotally connected to said printing head operable to permit the printing head to be swung selectively into co-operative relation to said platen and said inking pad, and other parallel arms extending from said rock shafts and connected by a link to ensure accurate movement of said printing head.

12. A marking machine comprising a platen and a work support providing an aperture in proximity to said platen in sufficient area to permit the portion of the flexible article which has been printed to be depressed therethrough a standard mounted on said work support, an inking pad located at the other side of said standard from said platen, parallel rock shafts mounted in said standard having parallel arms pivotally connected to said printing head operable to permit the printing head to be swung selectively into co-operative relation to said platen and said inking pad, and means connected to said standard tending normally to hold said printing head in an elevated intermediate position.

13. A marking machine comprising a

- work support and an inking pad, a printing head, means for supporting said printing head to permit it to swing from said inking pad to said platen while maintaining the printing face of said head in substantial parallelism with the plane of said work support, type-holding means in said head so constructed as to permit the type to be removed from the upper side of said type-holding means, and a depending locking device pivotally mounted upon an axis located above the type and normally engaging the upper end of the type. 14. A marking machine comprising a work support and an inking pad, a printing head, means for supporting said printing head to permit it to swing from said inking pad to said platen while maintaining the printing face of said head in substantial parallelism with the plane of said work support, type-holding means in said head so constructed as to permit the type to be removed from the upper side of said type-holding means, a depending locking device pivotally mounted upon an axis located above the type and normally engaging the upper end of the type. 15. A marking machine comprising a work support and an inking pad, a printing head having an inverted U-shaped body portion presenting downwardly extending arms, a type holder mounted in the lower ends of said arms so constructed as to permit the type to be removed from the upper side thereof, a depending locking device pivotally mounted in said arms to swing about an axis lying in substantially a longitudinal axial plane of the type and adapted to be swung with its lower edge into tangential engagement with the upper end of the type. 20

In testimony whereof, I have signed my name to this specification.

FRED A. PUTNAM. [L. s.]
